ALTERNATING CURRENT SWITCH
MECHANISM

Joseph F. Frese, Baltimore, Md., assignor to
Monitor Controller Company, Baltimore, Md.,
a corporation of Maryland

Application July 22, 1935, Serial No. 32,663

3 Claims. (Cl. 200—97)

This invention relates to mechanism for operating two electric switches or two pairs of switches so as to open and close them alternately. The apparatus is adapted particularly for use on alternating current circuits and comprises a solenoid having a coil and an external laminated core having two opposing pole pieces of like polarity and an armature movable between the pole pieces into and out of the coil. The armature is provided with a head adapted to fit flatly against the pole pieces. The armature is connected by springs to a rocking frame which directly operates the switches, and the frame is retarded in its movements by suitable retarding means. The arrangement is such that when the coil is energized the armature will be attracted and its head will find its natural seat against the pole pieces without interference by contact with the frame, thus avoiding a humming noise which might occur if the head were not properly seated, and the frame will then follow, under the tension of the springs, retarded by the retarding means. The armature is provided with a stop or distance piece which normally rests against the frame and against which the frame rests when pulled upward by the springs. The frame and armature return to normal positions by gravity when the solenoid is de-energized. When the frame is moved by the solenoid it opens a pair of normally closed switches and closes a pair of normally open switches and when the frame returns by gravity to its normal position it closes the former pair and opens the latter pair of switches. The switch arms of both pairs of switches are under spring tension while closed, to maintain good electrical contacts with the stationary members of the switches; but the arrangement is such that there is no spring tension to be overcome by the frame while the latter is returning to its normal position by gravity. Also there is no spring tension to be overcome by the frame while moving in the opposite direction, under the power supplied by the magnet until near the limit of the movement of the frame. Hence the springs associated with the switch arms do not hinder the rocking movement of the frame or apply an additional load on the armature of the solenoid until near the limit of movement of the frame, after the armature has been seated and there is plenty of power, supplied by the magnet, for operating the switches.

In the accompanying drawings,

Fig. 1 is a front elevation of the switch mechanism with the parts in their normal positions;
Fig. 2 is a right side elevation of the same;

Fig. 3 is a section on the line 3—3 of Fig. 1, the parts being shown in normal positions in full lines and the armature being shown in its upper position in dotted lines;

Fig. 4 is a similar view with the parts in the positions which they occupy when the magnet is energized;

Fig. 5 is a section through one of the normally closed switches, taken on the line 5—5 of Fig. 1;

Fig. 6 is a section through one of the normally open switches, taken on the line 6—6 of Fig. 1;

Fig. 7 is a similar view showing the switch closed;

Fig. 8 is an end view of the solenoid, and,

Fig. 9 is a side view of the armature.

Referring to the drawings, *a* indicates a suitable base of insulating material to the upper part of which is secured a bracket *b*. A solenoid *c* depends from the bracket, this solenoid comprising a laminated U-shaped core *1* having opposed pole pieces *1a* of like polarity at its lower end, an internal energizing coil *2*, and a movable armature *3* which extends between said pole pieces into the coil. The usual shading coil, embedded in the pole pieces, is indicated at *4*. The armature *3* is laminated and angular in cross-section and has a head *3a* which projects at its opposite sides and is adapted to seat flatly against the pole pieces when the coil is energized. A flat strip *5*, preferably of non-magnetizable metal, projects outwardly from the center of the head *3a* and this strip serves a purpose hereinafter described.

A pair of helical springs *6* connect the armature with a cross bar *8* on a rocking frame *d*. As shown, pins *9* project laterally from the center of the armature head, at its opposite sides, and the springs are connected to these and to the cross bar and normally hold the bar against the outer end of the flat metal strip *5*, which is midway between the springs. The rocking frame *d* comprises two similar side pieces *10* rigidly connected together by an angled cross piece *11*. Each side piece has a trunnion *12* and these trunnions are journaled in bearings *13* in supporting brackets *14*. A flat relatively heavy bar *15*, secured to the under side of the flange *11a* of the cross piece *11*, serves as a weight to rock the frame downwardly into the position shown in Figs. 1, 2, and 3, and ears *10a* on the side pieces of the frame are adapted to engage the upper edges of the brackets *14* and limit the downward movement of the frame. The side pieces have arms *10b* which project radially upward from the pivotal axis of the frame and these are connected by a round cross bar *16* which is adapted to engage

and operate a pair of switch arms e, e' , which are normally closed, and another pair of switch arms f, f' , which are normally open, as herein-after explained.

- 5 A dashpot cylinder g is secured to the under side of the horizontal plate of the bracket b , adjacent the solenoid, by bolts 17 , and this cylinder has a vent 18 in its upper end controlled by an adjusting screw 19 , to regulate the inflow and outflow of air to vary the retardation of the plunger 20 in the cylinder, as desired. A rod 21 , pivotally connected to the plunger at one end, has at its opposite end a perforated head 21^a through which the cross bar 8 on the rocking frame loosely extends.

The operation of the apparatus thus far described is as follows: When the coil of the solenoid is energized by the admission of alternating current thereto, the armature 3 is instantly drawn upward and its head 3^a seats itself against the flat surfaces of the pole pieces and the flat blade 5 is moved away from the cross bar 8 , as indicated in dotted lines in Fig. 3. The rocking frame, retarded by the dashpot, moves upward by the traction of the springs 6 , which are placed under tension by the upward movement of the armature, and when the frame reaches the position shown in Fig. 4, its movement is stopped by the engagement of the cross bar 8 with the end of the blade 5 which constitutes a distance piece or stop. This engagement of the cross bar with the distance piece does not disturb the armature. By retarding the movement of the rocking frame, while permitting the armature to move freely upward, the head of the armature will find its natural magnetic seat against the pole pieces without being hindered in this respect by any contact with any part of the frame and the humming noise which would occur if the head were prevented from finding its own seat is avoided. When the magnet is de-energized, its armature drops and since the stop or distance piece 5 is then in engagement with the cross bar 8 , the frame is rocked downwardly to normal position by the weight of the armature and the bar 15 , the dashpot cushioning this movement, and the ears 10^a on the frame, engaging the brackets 14 , limit the movement of the frame.

The switch arms e, e' are alike in structure and in their mountings, as are the contacts which they engage. One of these arms e , and the stationary contact 22 which it engages, is shown in Figs. 3, 4, and 5. The arm e has side flanges which are connected by a pivot pin 23 to a bracket 24 and a spring 25 coiled about the pivot pin and having one end engaging the base of the bracket and the other end engaging the arm constantly presses the arm away from the base a so that the contact on the arm normally engages the stationary contact 22 .

Normally the cross bar 16 on the rocking frame is out of engagement with the switch arms e, e' and these switches are closed, as shown in Figs. 3 and 5. When the magnet is energized, the frame is rocked and the bar presses against these switch arms and they are moved to open positions against the action of the springs 25 , as illustrated in Fig. 4. There is abundance of power in the magnet for causing the opening of the switches e, e' and when the magnet is de-energized, the springs move the switch arms to closed positions automatically and also, to a slight extent, assist the movement of the rocking frame to its normal position, at the commencement of the movement. During the final part of the move-

ment of the frame, cross bar 16 leaves the switch arms, as shown in Fig. 5.

While the switches e, e' are opened by the power of the magnet acting in opposition to the springs, and are self-closing by their springs 5 when the magnet is de-energized, the switches f, f' are closed by the power of the magnet but must be opened by the weight of the rocking frame and the armature when the magnet is de-energized. It is therefore desirable to avoid having spring pressure on the switches f, f' which would resist their opening movements and offer resistance to the falling movement of the rocking frame and armature, because such spring pressure would have to be compensated for by making the weighted bar 15 heavier for strong spring pressure than would be necessary for light spring pressure, and it is desirable to have this weight relatively small and standard for all switches. Therefore, the arrangement of the springs on the switch arms f, f' is such that they offer practically no resistance to the movement of the rocking frame when the switches f, f' are being opened, and yet tension is applied to the springs by the force of the magnet when these switch arms are in closed positions.

As shown in Fig. 6, the spring 26 is coiled around the pivot 27 on which the switch arm f is mounted and one arm 26^a of the spring engages the cross bar 16 of the rocking frame, while the other arm 26^b of the spring extends through an opening 28 in the switch arm and presses this arm against the cross bar, so that the switch arm and spring move together with the cross bar. When the magnet is energized, the bar 16 moves from the position shown in Fig. 6 to that shown in Fig. 7, carrying the switch arm into position to engage the stationary contact 29 without applying tension to the spring and then continuing a short distance further, thereby applying sufficient tension to the spring to provide a yielding contact between the switch members. When the magnet is de-energized and the rocking frame swings by gravity to its normal position, the bar 16 first relieves the tension on the spring and the spring and switch arm then move with the cross bar to the position shown in Fig. 6, free from spring resistance.

The mechanism is used as a timing device for controlling circuits. While it is especially adapted for use on alternating current circuits, it will be evident that it may be used on direct current circuits.

What I claim is:

1. In an electric switch mechanism, a switch member, a frame pivoted for rocking movement about a stationary axis, for operating said member, said frame being biased to one position, a solenoid for rocking the frame to another position, said solenoid comprising a coil and an external stationary core having opposed pole pieces of like polarity at one end and an armature movable between said pole pieces into and out of the coil and having a head adapted to seat against said pole pieces, said armature having a part normally engaging the frame and being movable away from the frame when the solenoid is energized, a spring connecting the armature with the frame, and means for retarding the movement of the frame.

2. In an electric switch mechanism, a switch member, a frame pivoted for rocking movement about a stationary axis, for operating said member, said frame being biased to one position, a solenoid for rocking the frame to another posi-

tion, said solenoid comprising a coil and an external stationary core having opposed pole pieces of like polarity at one end and an armature movable between said pole pieces into and out of the coil and having a head adapted to seat against said pole pieces, a distance piece secured to the armature and normally resting against the frame, said armature and distance piece being movable away from the frame when the solenoid is energized, a spring connecting the armature with the frame, and means for retarding the movement of the frame.

3. In an electric switch mechanism, a switch member, a frame pivoted for rocking movement about a stationary axis, for operating said mem-

ber, said frame being biased to one position, a solenoid for rocking the frame to another position, said solenoid comprising a coil and an external stationary core having opposed pole pieces of like polarity at one end and an armature movable between said pole pieces into and out of the coil, a distance piece secured to the armature and normally resting against the frame, said armature and distance piece being movable away from the frame when the solenoid is energized, a spring connecting the armature with the frame, and means for retarding the movement of the frame.
